AIR GUIDE FOR OIL BURNERS

Bowman K. Breed, Garden City, N. Y., assignor to
 Preferred Utilities Manufacturing Corporation,
 New York, N. Y., a corporation of Delaware

Application February 21, 1952, Serial No. 272,833

8 Claims. (Cl. 158—77)

1

This invention relates to oil burners and has particular reference to an improved arrangement for controlling the path of flow of the air supplied for combustion in burners of the mechanical atomizing type.

An object of the invention is to so control the flow of air discharged in an annular path surrounding the atomizing nozzle that intimate mixture of air and oil droplets is obtained.

Still another object is to so control the flow path of the air that it may be varied to obtain a wide or bushy flame or a narrow elongated flame, depending entirely upon the needs inherent for any particular installation.

Arrangements seeking these same objectives have been devised heretofore but for various reasons have proved unsatisfactory. A particular object of this invention is to eliminate the objectionable features of such arrangements as have been made available, such as circumferentially spaced radially extending flexible vanes which may be flexed to one position or another for controlling the path of air flow, described in Ruff Patent 2,280,638, and such arrangements as Ravnbeck 2,522,131 describes wherein the blades are composite in nature, one of the two component sections being adjustable with reference to the other about a pivot point to vary the overall contour of a continuous blade. In such structures as Ravnbeck discloses, and in all others of which I am aware, the guide blades which are in some way adjustable to vary the path of flow of the air are in effect continuous.

In carrying out my invention I utilize two rugged parts in the form of castings having integral therewith cooperating air guide blades or vanes, the two castings being rotatable with respect to each other to adjust for varying directional movement of the air. All of the pivot pins and interengaging parts subject to wear and tear, etc., which are a necessary part of the prior art devices to which reference has been made, are eliminated by my construction.

Still another object of the invention is to increase the flexibility and delicacy of adjustment for varying the nature of the flame obtained. Heretofore it has been customary when adjusting to change the direction of flow of all of the air discharged around the burner nozzle. The adjustment provided by my invention results in a change of direction of flow of some, only, of the air supply as distinguished from the total air supply and in effect results in a splitting of the flow, permitting some of the air to continue in a predetermined fixed path while deflecting the remainder of the air as desired.

2

Various other objects and meritorious features of the invention will become apparent from the following description taken in conjunction with the drawings, wherein like numerals refer to like parts throughout the several figures, and wherein:

Fig. 1 is a longitudinal section through a burner embodying my improved air guide;

Fig. 2 is a section along line 2—2 of Fig. 1;

Fig. 3 is a front elevation of the air guide plate;

Fig. 4 is a section through 4—4 of Fig. 3;

Fig. 5 is a rear elevation of the cover for the fan casing, and

Fig. 6 is a partial section along 6—6 of Fig. 5.

My invention has been illustrated as embodied in a more or less conventional type of rotary oil burner of the mechanical atomizing type which embodies an oil feed tube 10 through which oil under pressure is supplied to a fuel tube tip 12 surrounded by a motor-driven rotary atomizing cup 14.

Within the fan casing 16 is a rotary fan 18 which is motor driven. Fan casing cover 20 is secured to the casing by means of circumferentially spaced bolts 22, the cover being flared outwardly to form a central opening in the form of a tapered air discharge nozzle 24 which surrounds the atomizing assembly. Other conventional parts are secured integrally with the cover 20, such as the nozzle shield 26 within which is an igniter assembly 28 and the ignition junction box 30 which is secured to furnace plate 32 surrounding the nozzle shield.

Referring now particularly to my improved air guide arrangement, a series of curved vanes or blades 34 are cast integrally with fan casing cover 20. These blades are spaced circumferentially around the outer marginal inside surface of the cover, as clearly shown in Fig. 2. In the arrangement disclosed wherein there are six blades or vanes 34 cast integral with the casing cover 20, each alternate blade is provided at its inner end with a lug 36 which is bored and internally threaded to receive a bolt for purposes to be described hereinafter.

Cooperable with the cover 20 and its integrally cast inwardly extending vanes 34 is a guide plate 38 which is of substantially the same diameter as the cover plate 20, but somewhat less for reasons that are apparent. Cast integrally with guide plate 38 are a series of vanes or blades 40 which are spaced circumferentially around the plate in the same manner as vanes 34 and are adapted to cooperate therewith. Circumferentially spaced around guide plate 38 outside the outer margins 55 of vanes 40 are a series of arcuate slots 42

which are adapted to register with lugs 36 on fan casing cover 20.

The plate 38 is secured to cover 20 by means of bolts 44 which extend through slots 42 and are threaded into lugs 36, the flat head of bolt 44 in each instance functioning to secure the two elements against rotation after they have been set in the desired adjusted position.

The air traveling circumferentially around the outer margin or periphery of fan casing 16 will be deflected by blade 34 integral with the casing cover 20 from movement in a counterclockwise direction to movement in a longitudinal plane of the oil shaft. If not further turned, this air would travel forward through the passage around the atomizer and leave the air nozzle traveling parallel to the shaft. A narrow, long, straight fire would result.

However, vanes 34 are, in effect, extended by secondary vanes 40 which further turn the incoming air and cause it to follow a clockwise rotation around the shaft. This clockwise rotation is maintained as the air moves forward toward the air nozzle. The degree of rotation determines the angle of the fire. If maximum clockwise rotation is provided by secondary vanes 40 the angle of fire will be increased. The flame will be wide and short and have a maximum atomization and flame retention. This maximum effect is obtained when the air guide casting 38 having integral therewith the secondary vanes 40 is so adjusted that primary vanes 34 and secondary vanes 40 are in alignment. This position is illustrated in Fig. 2 and obtains when flat-headed bolts 44 are at one limit of their permissible movement in slots 42. This end of the slot may be designated W, signifying a wide flame, and the other end of the slot may be designated N, signifying a narrow flame adjustment.

When the secondary vanes 40 are rotated out of alignment with primary vanes 34, some of the air flowing inwardly from the periphery of the fan casing will not impinge upon the secondary vanes 40 and thus will be only straightened. Another portion of the air flowing inwardly will impinge upon both the primary vanes 34 and the secondary vane 40, and as a result of this impingement on secondary vane 40 the air so impinging will be deflected into a rotary path. The combination of the two effects will result in less clockwise rotation of the air in its entirety and the angle of fire will be decreased.

As will be apparent from the description thus far, the angle of fire may be varied from "wide" to "narrow" by merely rotating the air guide plate 38 from the position designated W toward the position designated N. This is accomplished simply by removing bolts 22, which permits removal of fan casing cover 20. The three flat-headed screws 44 may then be loosened, the air guide casting rotated as desired, and the screws retightened. The casing cover 20 may then be replaced.

My improved arrangement, while not providing external adjustment, possesses the important advantage of simplicity and ruggedness which more than offsets the complications inherent in devices earlier described. It eliminates all possibility of rattling and all danger of loss of adjustment in the vanes, a very frequent and undesirable feature which inheres in the various known mechanisms available for this purpose. One or two trial adjustments of my construction will result in the desired settings, although for most installations the construction is such that

the "wide" or W position will prove most advantageous.

It should also be noted that air guide plate 38 with its integral secondary vanes 40, eliminates the need for a separate baffle plate used in conjunction with the continuous vanes of available devices. Such baffle plates are secured separately in the assembly and, in addition to the vanes, constitute elements which must be serviced and regulated.

Having described a preferred embodiment of my invention, various modifications will be apparent to those skilled in the art and for that reason I wish to limit myself only within the scope of the appended claims.

What I claim is:

1. In an oil burner, the combination of a casing means having a longitudinal axis and axially spaced walls, one of said walls having a discharge opening positioned transversely of the centered about said longitudinal axis, means for providing a source of air at the outer periphery of the space between said spaced walls, air control means including outer air control means leading from said source of air and inner air control means discharging at said discharge opening, said outer air control means being positioned between said walls and defining inwardly extending primary air passages for channeling the flow of air from the outer periphery of said walls inwardly toward said inner air control means, said inner air control means being positioned between said walls and defining inwardly extending secondary air passages for channeling the flow of air from the outlet of said outer air control means to said discharge opening, said primary and secondary air passages when in alignment forming a plurality of continuous passages from the outer periphery of said walls to said discharge opening, and adjusting means for enabling predetermined disalignment of said primary and secondary air passages for forming discontinuous passages, the air from each of said primary air passages being divided and passed through two adjacent secondary air passages when said primary and secondary air passages are disaligned.

2. In an oil burner, the combination of a casing means having a longitudinal axis and axially spaced walls, one of said walls having a discharge opening positioned transversely of and centered about said longitudinal axis, means for providing a source of fuel at said opening, means for providing a source of air at the outer periphery of the space between said spaced walls, air control means including outer vanes and inner vanes, said outer vanes being positioned between said walls and defining inwardly extending primary air passages for channeling the flow of air from the outer periphery of said walls inwardly toward said inner vanes, said inner vanes being positioned between said walls and defining inwardly extending secondary air passages for channeling the flow of air from the outlet of said outer vanes to said discharge opening, said primary and secondary air passages when in alignment forming a plurality of continuous passages from the outer periphery of said walls to said discharge opening, and adjusting means for enabling predetermined disalignment of said primary and secondary air passages for forming discontinuous passages, the air from each of said primary air passages being divided and passed through two adjacent secondary air passages when said primary and secondary air passages are disaligned.

3. In an oil burner in accordance with claim 2 and wherein said outer vanes are contoured to control the flow of air thereover in a manner such that the flow is urged in a direction along said longitudinal axis and wherein said inner vanes are contoured to control the flow of air thereover in a manner such that the air is urged to rotate about said longitudinal axis.

4. In an oil burner in accordance with claim 3 and wherein said means for providing a source of air at the outer periphery of the space between said spaced walls comprises a blower operable to create a flow of air in a circular path.

5. In an oil burner the combination of a casing means with a longitudinal axis having a cover and a wall plate axially spaced from said cover, said cover having a discharge opening positioned transversely of and centered about said longitudinal axis, means for providing a source of fuel at said opening, a blower mounted in said casing operable to create air flow in a circular path at the outer periphery of the space between said cover and said wall plate, air control means including outer and inner air control means, said outer air control means comprising identical, arcuate, primary vanes circumferentially spaced around and integral with said cover, said primary vanes defining primary air passages for channeling the flow of air from said outer periphery toward said inner air control means, said inner air control means comprising identical, arcuate, secondary vanes circumferentially spaced around and integral with said wall plate, said secondary vanes defining secondary air passages for channeling the flow of air from said primary air passages to said discharge opening, said primary and secondary vanes when in alignment forming a plurality of continuous passages from said outer periphery to said discharge opening, and adjusting means for enabling predetermined

disalignment of said primary and secondary air passages for forming discontinuous passages, the air from each of said primary air passages being divided and passed through two adjacent secondary air passages when said primary and secondary air passages are disaligned.

6. In an oil burner in accordance with claim 5 and wherein said primary vanes are contoured to control the flow of air thereover in a manner such that the flow is urged from its circular path into a direction along said longitudinal axis and wherein said secondary vanes are contoured to control the flow of air thereover in a manner such that the air is urged to rotate about said longitudinal axis in a circular path counter to its original direction of movement.

20 7. In an oil burner in accordance with claim 6 and said cover having circumferentially spaced, internally threaded lugs, said wall plate having arcuate slots at circumferentially spaced locations corresponding to the lugs on said cover, and bolts extending through said slots into said lugs, thereby enabling alignment or predetermined disalignment of said primary and secondary vanes.

25 8. In an oil burner in accordance with claim 7 and wherein said means for providing a source of fuel comprises a rotatable oil atomizing cup having its axis aligned with said longitudinal axis.
